UNITED STATES PATENT OFFICE

DANIEL SNYDER GUSTIN, OF BLOOMFIELD, NEW JERSEY, ASSIGNOR TO WESTINGHOUSE LAMP COMPANY, A CORPORATION OF PENNSYLVANIA

ARC QUENCHING DEVICE

Application filed January 11, 1928. Serial No. 245,821.

This invention relates to electric incandescent lamps and more particularly to gas filled lamps having means therein for extinguishing an arc occurring between the lead wires of the lamp.

Although the present invention is applicable to various types of lamps, it is preferably applied to gas filled lamps and particularly to such type of lamp in which a number of lamps designed for a relatively low voltage are operated in series on circuits of about 200 to 600 volts or more as in street lighting and street railway lighting practice.

Heretofore, during the operation of such lamps, certain disadvantages occurred by reason of an arc forming between the lead wires of the lamp when the filament failed. It has been found that an arc forming between the lead wires is maintained for a considerable length of time and often not only traverses the leading-in wires to the stem-press or lower portion of the lamp, but will actually burn a path through the stem-press and continue into the base portion of the lamp fusing the metallic base into the socket or often destroying the socket and injuring the adjacent parts.

The formation of destructive arcs in lamps has been appreciably increased by the use of argon as a gaseous filling for lamps instead of nitrogen, since argon permits the formation and maintenance of the arc more readily than does nitrogen, and although the present invention is practical in an argon filled lamp, it has been found that more advantageous results are obtained when a nitrogen filling is employed.

It will be evident that where lamps are operated in series, as, for example, where five 110 volt lamps are operated in series in a 550 volt circuit, a considerable area might be turned into darkness should one lamp burn out. Means are, however, provided in the form of various well known devices for closing the circuit around each lamp in case it burns out. Some of such devices are incorporated in the socket or in the socket holder and in order that they may be successfully operated, it is essential that an interruption of the current be effected when the

filament fails. Should an arc form between the leading-in wires and continue to permit a flow of current, the cut-out device would not operate and as will be evident, the arc may continue to the destruction of the said devices.

An object of the present invention is to provide a simple and effective means for terminating an arc within a sealed envelope.

Another object of the invention is to provide an arc quenching medium so disposed with relation to the leading-in wires as to terminate an arc occurring therebetween.

Another object of the invention is to provide a medium between the leading-in wires of a lamp of such character that when an arc occurs the said medium will evolve gas or gases tending to snuff the arc.

Other objects and advantages of the invention will be apparent as the description proceeds.

The invention will be more fully understood by reference to the accompanying drawings in which:

Fig. 1 is an elevational view of a lamp embodying the present invention, partly broken away to show the interior thereof; and

Fig. 2 is a transverse sectional view taken on line II—II in Fig. 1.

Although the present invention may be applied to any suitable incandescent electric lamp, it is shown and described in the drawings as embodied in a gas-filled, ring type filament lamp comprising a bulb 10 having the usual flare tube 11 sealed at 12 to the bulb. The flare tube is of the usual hollow form having one end terminating in a press 13 from which an arbor 14 extends. The arbor is provided with support wires 15 upon which a filament 16 is mounted. Leading-in wires 17 and 18 extend through the press 13 and downwardly through the flare tube 11.

The type of bulb shown includes an exhaust tube 18' which occupies the center of the flare tube, this construction being common to the so-called tipless lamp. The lamp may be provided with the usual base 19 in which the leading-in conductors 17 and 18

are electrically connected in the usual manner at 20 and 21.

Normally, the leading-in wires or conductors 17 and 18 extend through the hollow portion of the flare tube 11 and if the filament 16 breaks and an arc occurs between the leading-in wires it would be possible for the said arc to continue through the said flare tube and down into the base. For the purpose of 10 quenching the arc before it reaches the base, the flare tube 11 may be filled with a substance 22 capable of offering a barrier between the leading-in wires to quench or snuff the arc.

It has been found that a preferable material for this purpose is magnesium carbonate. In practice, the said magnesium carbonate is utilized in a finely divided state and is poured into the flare tube until it fills the same. The powder may then be packed by tamping until 20 it is compressed and firmly packed about the leading-in wires after which a collar or washer 23, preferably of felt, may be forced into the flare tube with a tight fit to hold the powder in place. If desirable, the washer may 25 be further secured by applying a layer of a suitable cement 24 thereover.

When a lamp constructed as above set forth is put into operation and the filament fails causing an arc between the leading-in wires, 30 the said arc may travel down the leads until it is interrupted by the interposed barrier of arc quenching material at which time the conductive passage necessary for supporting an arc will be destroyed and the arc terminated.

When employing the present arc quenching medium in an argon filled bulb, it has been found that although the argon tends to support an arc, the present arc quenching material serves to break down the arc when said 40 material is reached. When using the said arc quenching material such as magnesium carbonate or like substance in a lamp having a nitrogen gas filling, it has been found that the gas evolved, which in the present instance is 45 CO_2 gas, cooperates with the nitrogen to terminate the arc.

It is believed that the present arc quenching material is of such character as to absorb or dissipate electrons to such degree as to 50 terminate the arc. The invention, therefore, contemplates any finely divided material such as magnesium carbonate which will cooperate with the gas within the bulb to terminate an arc produced between elements 55 separated by the arc quenching medium.

By reason of the present invention, a lamp may be produced with arc quenching means in a rapid and practical manner and at a cost comparable with other lamp making operations. It is appreciated that various types of 60 arc quenching devices have been produced, but the present invention utilizes the standard structure of a lamp for the support of the arc quenching medium, thus avoiding any 65 change in the accepted lamp structure and

making the invention applicable to all types of universally used lamps.

Although a preferred embodiment of the invention is shown and described herein, it is to be understood that modifications may be 70 made therein without departing from the spirit and scope of the invention as set forth in the appended claim.

What is claimed is:

An electric incandescent lamp comprising 75 a bulb containing nitrogen, leading in wires supported within said lamp, a filament mounted on said leading in wires and a quantity of finely divided magnesium carbonate disposed between and in contact with leading 80 in wires whereby gases evolved from the magnesium carbonate upon the formation of an arc between the lead wires cooperate with the nitrogen filling to terminate the arc.

In testimony whereof, I have hereunto subscribed my name this 10th day of January, 1928.

DANIEL SNYDER GUSTIN.
